UNITED STATES PATENT OFFICE.

FRANCIS F. HAMILTON, OF INDIANAPOLIS, INDIANA.

DESIGN FOR A CHEST.

Application filed January 3, 1925. Serial No. 11,872. Term of patent 14 years.

To all whom it may concern:

Be it known that I, FRANCIS F. HAMILTON, a citizen of the United States, residing at Indianapolis, in the county of Marion and State of Indiana, have invented a new, original, and ornamental Design for a Chest, of which the following is a specification, reference being had to the accompanying drawing, forming a part thereof.

The single figure of the drawing is a perspective view of a chest embodying my new design.

I claim:

The ornamental design for a chest, as shown.

FRANCIS F. HAMILTON.
